Specification for Design.

Patented June 1, 1920.

Application filed September 15, 1919. Serial No. 324,030. Term of patent 14 years.

To all whom it may concern:

Be it known that I, GEORGE B. HOVEKAMP, a citizen of the United States of America, and a resident of Cincinnati, in the county of Hamilton and State of Ohio, have invented a new, original, and ornamental Design for Rosaries, of which the following is a specification.

The figure is a plan view of a rosary showing my new design.

I claim:

The ornamental design for a rosary as shown.

In testimony whereof, I have hereunto subscribed my name this 12th day of September, 1919.

GEORGE B. HOVEKAMP.
